(57) **CLAIM**

The ornamental design for a control lever for construction equipment, as shown and described.

DESCRIPTION

FIG. 1 is a front perspective view of a control lever for construction equipment showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines are shown for illustrative purposes only and form no part of the claimed design.

1 Claim, 6 Drawing Sheets

FIG. 1

FIG. 2***FIG. 3******FIG. 4******FIG. 5******FIG. 6****FIG. 7**FIG. 8*
